ATTORNEYS

UNITED STATES PATENT OFFICE.

HERMAN MATZEN, OF BEDFORD, OHIO.

DESIGN FOR A CHAIR-BACK.

SPECIFICATION forming part of Design No. 18,824, dated December 25, 1888.

Application filed September 27, 1888. Serial No. 286,601. Term of patent 3½ years.

To all whom it may concern:

Be it known that I, HERMAN MATZEN, a citizen of the United States, residing at Bedford, in the county of Cuyahoga and State of Ohio, have invented and produced a new and original Design for a Chair-Back, of which the following is a specification, reference being had to the accompanying drawing, forming a part thereof.

10 The figure is a front side elevation.

A A represent the posts of the chair-back, each post at the top end thereof being finished to represent an ear of corn, *a*, with the husks thereof turned down in loops, as shown at *a'*, and joining the body of the work at or near the butt of the ear. At the lateral center and top of the chair-back, at B, is a carved figure designed to represent the typical grandmother's face, the same being set in a 15 groundwork of old-time broad ruffle, *b*.

The leading features of the design are the representations of the ears of corn at the upper ends of the side posts and the representation of the typical grandmother's face at the top of the chair-back. 25

What I claim is—

1. The design for a chair-back, consisting of the shape shown.

2. In the design for a chair-back, the design for the upper ends of the posts, as shown. 30

3. In the design for a chair-back, the design for the top of the chair-back, as shown.

In testimony whereof I sign this specification, in the presence of two witnesses, this 21st day of April, 1888.

HERMAN MATZEN.
